BELL CRANK CLOSURE

Charles H. Schnorr, New Kensington, Pa., assignor to Cornell Securities Corporation, Cleveland, Ohio, a corporation of Delaware

Application November 13, 1935, Serial No. 49,544

6 Claims. (Cl. 220—61)

My invention is an improvement in metallic receptacles or containers of the full removable open head type, and relates more particularly to a clamping or locking device for removably securing the heads to containers of this type in fluid tight sealed relation.

One of the objects of my invention is to provide a simple clamping device comprising broadly a channelled band which may be contracted to press portions of the receptacle and cover together in fluid tight sealed relation and simple mechanism carried by the band within its circumference for contracting the same.

Another object of the invention is to provide a mechanism for contracting the band which includes a lever fulcrumed to one end of the band at a point remote from the ends of the lever and a member connecting one end of the lever with the other end of the band.

A further object of the invention consists in a clamping device in which the lever and the connecting member operate in opposite directions and about a fulcrum which is located at a point for producing increased closing forces and consequently to provide a better seal between the cover and the receptacle. In this manner the ends of the band or ring, when the ring is contracted, will be caused to move together simultaneously with a pulling movement on the ends 30 of the ring toward the vertical axis of the container.

Other objects and advantages of this invention will become more apparent as the following description of an embodiment thereof progresses, reference being made to the accompanying drawing in which like reference characters are employed to designate like parts throughout the same.

In the drawing:

40 Figure 1 is a top plan view of an embodiment of my invention, showing the cover on the receptacle in closed fluid tight sealed relation.

Figure 2 is an enlarged fragmentary section taken on line 2—2 of Figure 1.

45 Figure 3 is a fragmentary plan view of the locking or clamping ring contracted to seal the cover on the receptacle.

Figure 4 is a view similar to that of Figure 3 except that the ring is shown partly expanded 50 as in removing the ring and cover from the receptacle.

Figure 5 is a fragmentary view in elevation taken in the direction of line 5—5 of Figure 3.

My invention is particularly applicable to metallic containers or receptacles such as drums

or barrels, or the like, which are provided with a circumferential bead at the open end thereof for supporting a cover and for reinforcement purposes.

Referring to the drawing in which I have illustrated an embodiment of my invention the barrel or drum is indicated at 1. The upper open end of the container is formed with a circumferential bead 2. A cover 3 comprises a cupped member having a circumferential upwardly and outwardly extending flange 4, supported by the bead 2 in such a manner that the cupped portion of the cover may be telescoped for a short distance within the open end of the channel as illustrated in Figure 2. It will be noted that a portion of the flange 4 is slightly arcuate in cross section to conform with the approximate curvature of the upper surface of the bead. A packing ring 5 is interposed between the cover flange 4 and the bead 2 and may consist of an annulus of any suitable packing material, such as cork or flexible rubber tubing.

I have provided a simple means for removably securing the cover on the receptacle in fluid tight sealed relation by exerting a substantially uniform pressure on the cover and the bead in a direction substantially parallel to the vertical axis of the container.

In the present embodiment this means includes a split contractible clamping ring 6 of channelled cross section, the upper and lower flanges of the ring defining the channel being engageable respectively with the cover flange 4 and the under surface of the bead 2. These flanges converge outwardly of the ring and it will thus be seen upon contracting the ring the cover flange and the bead of the receptacle will be pressed tightly against the packing 5 under a substantially vertical pressure.

The ends of the clamping band or ring 6 are provided with inwardly extending lugs or brackets 7 and 8 respectively which may be formed separately or welded thereto. The lug 8 is of greater length than the lug 7, that is, it extends inwardly of the ring to a point considerably beyond the inner extremity of the lug 7.

An operating lever 9 is pivotally carried by the longer lug 8 by means of a headed pin 10. The pin 10 is fitted in an opening in the lever at a point substantially remote from the ends of the lever as is clearly shown in Figures 3 and 4. The lever 9 comprises essentially a bell crank having two arms 9 and 11. Each of these arms is preferably arched as illustrated, and arranged to intersect one another, the shorter arm 11 pro-

jecting inwardly of the arm 8 toward the center of the ring when the lever is assembled as shown in the drawing. It is to be noted that the free end of the arm 11 projects beyond the lug 8 at 5 a point spaced inwardly of the ring when the lever is in closed position, but the length of the arm 11 from the fulcrum point of the lever to its outer free end is such that the lever may be swung to the right as in Figure 4 to expand 10 the ring without interference with the cover flange 4.

A connecting link or other suitable member 12 is pivotally connected at one end to the lug 1 by means of a headed pin 13, and at its other end 15 to the outwardly projecting free end of the arm 11 of the lever by means of a headed pin 14 as shown in Figures 3 and 4. The link 12 preferably is positioned in a plane between the respective planes of the lugs 7 and 8 and the plane of 20 the lever 9 so that when the lever is pulled to the left in the figures the closing forces exerted through the lever and link to the lugs and consequently to the ends of the rings are uniformly 25 distributed without any tendency to pull the ends of the ring out of line either vertically or horizontally. It will be noted that when the lever is swung to closed position to contract the ring the movement of the link is in a right hand 30 direction in the figures while the movement of the longer arm of the lever is in a substantially opposite direction, and that as the lever 9 approaches the full closed position the link 12 is caused to move inwardly of the ring toward the pin 10 thus bringing the centers 13, 10, and 14 35 close to a dead center position. In this manner it will be observed that as the centers approach a dead center position the manual forces required to bring the lever 9 to its extreme position in the left of the figure will be diminished as the lever approaches that position. As shown in Figure 1 the lever 9 which constitutes an operating handle 40 may be retained in ring contracting position by means of a retaining lug 15 carried by the ring and extending inwardly and downwardly thereof.

45 The operation of the device is simple. In sealing a cover on a receptacle the cover is first telescoped within the open end of the receptacle so that the cover flange 4 is seated upon the packing ring 5 and bead 2 as shown in Figure 2. The clamping ring or band is expanded by moving the lever to a right hand position and is fitted over the covered end of the receptacle and the lever 9 is pulled to the left as shown in Figure 4 sufficiently to bring the channel of the ring into 50 position so that the flanges defining the channel engage the cover flange 4 and the under surface of the bead 2. When the ring is thus in the proper position for final sealing, the operator grasps the handle portion of lever 9 and swings it to the extreme left hand position to fully contract the ring and thereby press the cover flange and receptacle together in fluid tight sealed relation. To remove the cover from the receptacle 55 this operation is reversed.

60 I have found that by extending the fulcrum of the lever inwardly of the ring to a greater distance than that of the fulcrum defining the connection between one end of the ring 12 and the lug 7, the device is easier to operate and a very effective fluid tight seal can be obtained between the cover and the receptacle. Furthermore, by extending one arm of the lever inwardly of the ring in closed position and pivotally connecting the same with the longer lug 8, a connection 65 between the end of the lever and the lug 7 secured

to the other end of the ring, can be made which further adds to the simplicity of the device and the effectiveness of its operation.

In Figure 3 it will be noted that the lever 9 is formed so that the heel portion 16 presses outwardly against the side wall of the drum head 3 when the lever is swung toward ring contracting position. This is a distinct advantage in that it first pulls the end of the ring carrying the bracket 1 inwardly of the drum to press the cover and container together at this point and as the lever continues to move to the left to full closed position this pressure is maintained simultaneous with a similar inward pressure which is exerted through the bracket 8 to pull the other end of the ring inwardly and circumferentially toward the first named end of the ring. In this manner both ends of the ring are brought close together when the ring is contracted and are made to firmly press the cover and receptacle together at 20 these points, thus providing a tight seal between the cover and receptacle throughout the extent of the ring.

Various changes may be made in the details of construction and arrangement of parts without departing from the spirit of the invention or the scope of the appended claims.

I claim:

1. In a clamping device for a metallic receptacle having a bead formed about its open end and a cover having a flange fitting over the bead, a split channelled clamping ring having portions engaging the bead and cover flange to press the same together when the ring is contracted, lugs projecting inwardly of the ring and means for contracting and expanding the ring, said means including a lever pivotally connected at a point intermediate its ends with one of said lugs, and a link pivotally connected at one end with another of said lugs and at its other end with the inner 30 end of said lever.

2. In a clamping device for a metallic receptacle having a bead formed about its open end and a cover having a flange fitting over the bead, a split channelled clamping ring having portions engaging the bead and cover flange to press the same together when the ring is contracted, lugs projecting inwardly of the ring and means for contracting and expanding the ring, said means including a bell crank lever fulcrumed at a point 35 remote from its ends to one of said lugs, and a member pivotally connecting the other of said lugs with the inner end of said lever.

3. In a clamping device for a metallic receptacle having a bead formed about its open end and a cover having a flange fitting over the bead, a split channelled clamping ring having portions engaging the bead and cover flange to press the same together when the ring is contracted, lugs projecting inwardly of the ring and means for contracting and expanding the ring, said means including a lever comprising an operating handle and a complementary part offset from the handle portion, said lever being pivotally connected with one of said lugs in the vicinity of the junction between the handle and offset portions, and a member pivotally connecting another of said lugs with said complementary offset part of the lever.

4. In a clamping device for a metallic receptacle having a bead formed about its open end and a cover having a flange fitting over the bead, a split channelled clamping ring having portions engaging the bead and cover flange to press the same together when the ring is contracted, lugs projecting inwardly of the ring and means for con-

tracting and expanding the ring, said means including a lever pivotally connected with one of said lugs and extending toward and beyond another of said lugs, said lever comprising a pair of 5 arched intersecting arms and a link connecting the other lug with the inner end of the lever.

5. In a clamping device for a metallic receptacle having a bead formed about its open end and a cover having a flange fitting over the bead, a 10 split channelled clamping ring having portions engaging the bead and cover flange to press the same together when the ring is contracted, lugs projecting inwardly of the ring and means for contracting and expanding the ring, one of said 15 lugs extending inwardly of the ring for a greater distance than another of said lugs, said means including a lever pivotally connected with said longer lug and extending toward and beyond said other lug, and a member pivotally connecting said 20 other lug with the inner end of said lever.

6. In a clamping device for a metallic receptacle having a bead formed about its open end and a cover having a flange fitting over the bead, a split channelled clamping ring having portions engaging the bead and cover flange to press the 5 same together when the ring is contracted, lugs projecting inwardly of the ring and means for contracting and expanding the ring, said means including a lever comprising a rigid member generally S-shaped in contour and having its fulcrum located remote from the ends thereof, said lever being pivotally connected at its fulcrum with one of said lugs, and a link pivotally connecting the other of said lugs with the inner end 10 of said lever, a portion of said lever remote from its ends being engageable with the cover flange for exerting a lateral pressure thereagainst when the ring is contracted.
